(57) **CLAIM**

We claim the ornamental design for an electronic device, as shown and described.

DESCRIPTION

FIG. 1 is a rear perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The broken lines that are immediately adjacent to the shaded areas and define unshaded regions, represent the bounds of the claimed design. The broken lines that are shown within the broken line boundaries and the broken lines outside of the claim are directed to environment. The broken lines form no part of the claimed design.
